FIG. 7

FIG. 8

FIG. 9

FIG. 10

FIG. 11

FIG. 1 is a front left perspective of a copying machine showing my new design.

FIG. 2 is a front right perspective of the copying machine shown in FIG. 1.

FIG. 3 is a left rear perspective of the copying machine shown in FIG. 1.

FIG. 4 is a right rear perspective of the copying machine shown in FIG. 1.

FIG. 5 is a front left perspective view of the copying machine shown in FIG. 1 wherein a cover portion has been moved to an open position.

FIG. 6 is a front right perspective view of the copying machine shown in FIG. 1 wherein the cover portion has been moved to an open position.

FIG. 7 is a left side elevational view of the copying machine shown in FIG. 1.

FIG. 8 is a right side elevational view of the copying machine shown in FIG. 1.

FIG. 9 is a top plan view of the copying machine shown in FIG. 1.

FIG. 10 is a rear elevational view of the copying machine shown in FIG. 1.

FIG. 11 is a front elevational view of the copying machine shown in FIG. 1.

I claim:

The ornamental design for a copying machine or the like, substantially as shown and described.
